UNITED STATES PATENT OFFICE.

ANDREW B. MILLER, OF BALDWIN, WISCONSIN.

DRY-CLEANING AND WASHING MACHINE.

1,313,497.

Specification of Letters Patent.

Patented Aug. 19, 1919.

Application filed March 28, 1918. Serial No. 225,154.

To all whom it may concern:

Be it known that I, ANDREW B. MILLER, a citizen of the United States, residing at Baldwin, in the county of St. Croix and

5 State of Wisconsin, have invented a new and useful Dry-Cleaning and Washing Machine, of which the following is a specification.

My invention relates to machines for dry-cleaning clothes, and the object is to provide an economical, cheap, practical and fast working machine of such convertible construction that by slight adjustment of some of the parts the same one machine will 10 clean the clothes by gasolene and then extract the gasolene from the clothes, and when so desired the machine may be used as an ordinary clothes washing machine.

In the accompanying drawings:

20 Figure 1 is a top view of the machine with the cover omitted. Fig. 2 is a section on the line 2—2 in Fig. 1. Fig. 3 is an enlarged section on the line 3—3 in Fig. 1, showing the end of the frame 37 and the 25 adjacent mechanism mounted therein. Fig. 4 is an inside view of the lower bearing member 54 in Fig. 3. Fig. 5 is a bottom end view of Fig. 4. Fig. 6 is a detail view of the end of the frame 37 with the lower 30 journal bearing and all mechanism omitted. Fig. 7 is a partly sectional front elevation of the machine and its cover with the pounders in such positions as may best show their parts. Fig. 8 is a bottom view of 35 either one of the two pounders employed. Fig. 9 is a sectional top view on the line 9—9 in Fig. 7. Fig. 10 is a bottom view of Fig. 9.

40 Referring to the drawings by reference numerals, 1 designates the main tub. It is riveted at 2 to a bottom 3, which rests on legs 4 and is provided with radial grooves 5 and a depression 6 having a pet-cock or valve 7 through which to empty the gasolene out from the machine. The tub is also 45 provided with a cover 8 having a handle 9.

Spaced within the tub 1 is a cylinder 10 having perforations 11 in its bottom and in the lower portion of its wall. Said cylinder 50 has its bottom 10^a fixed on a central vertical shaft 12 whose lower end is journaled in a ball-bearing 13 in the bottom of the tub, and the upper end is journaled in the leg of a T-shaped member 14, in whose upper 55 portion and in bearings 16, 17 fixed on the tub, is journaled a horizontal operating shaft

15, which is provided with a handle 18 and a pulley 19 so it may be turned by either hand power or a belt where motive power is available.

60 Fixed on the shaft 15 is a gear wheel 20 near which is journaled on the shaft an arm 21 having two studs 22, 23. On the latter stud is journaled a combined gear wheel 24 and a small grooved friction pulley 25. Said pulley is adapted to engage frictionally 65 the upper edge of the cylinder 10 and rotate it slowly since the gear 24 is larger than gear 20 which drives it by means of an idler gear 26 on stud 22.

70 The arm 21 is normally impelled downward by means of a spring 27 (see Fig. 2) so as to cause the friction pulley 23 to engage and rotate the cylinder, but such engagement may be put out of action by supporting the free end of the arm 21 in a notch 28 of a support 29, which is pivoted at 30 to the tub and is idle when leaning against a pin 31 fixed in the side of the tub. Slidably fitted on the shaft 15 and a feather-key 32 in same is a bevel gear 33 having a set-screw 34 adapted to hold it either in mesh or out of mesh with a bevel pinion 35 fixed on the vertical shaft 12.

75 Fixed on the shaft 15 are also two mutilated gears 36, 36^a, each of which has its toothed portion turned toward the side of the shaft 15 where the untoothed portion of the other gear is directed. Detachably journaled on the shaft 15 is a frame 37 having 80 vertical channel bearings 38, in which are slidably fitted pounder bars 39 having each a rack 40 arranged to be engaged by the adjacent mutilated gear, 36 or 36^a. The lower end of each pounder bar is provided 85 with a piston shaped pounder 41, which is movable up and down in a cylinder 42, whose bottom is open except for a spider 43 (see Fig. 8) which prevents the clothes from getting sucked too far into the pounder 100 cylinder. The spider 43 is provided with a central upward stem or rod 44 which steadies the cylinder by sliding in the tubular lower part of the pounder bar.

105 On each pounder bar is secured a collar 45, above which is a spring 46 adapted to act as a cushion up under the frame 37; and below said collar is a much longer spring 47, the function of which is to yieldingly press the cylinder 42 down upon 110 the clothes operated on.

The top of each cylinder 42 is provided

with two apertures 48, through each of which extends from the piston 41 a light link rod 49, from the top of which extends a light contractible coil spring 50, having 5 its upper end attached to an arm 51 of the frame 37.

In order to make the frame 37 readily detachable from the shaft 15 its journal bearings on said shaft are each formed of an 10 upper rigid half bearing or box 52 (see Figs. 3 and 6) and a lower half box 53. The latter is formed in the upper end of a heavy plate 54 having a recess 55 fitting the edges 56 of the frame when the portion 53 15 fits the underside of the shaft. In this position the member 54 is held by a spring 57 (shown in Fig. 7) placed upon a rod 58, which extends from the member 54 through a slotted hole 59 in a post 60 on the frame 20 (see Figs. 6 and 7) and is provided with a washer 61 and pin 62 which hold the spring at all times partly compressed against the post 60. When the frame is to be removed the bearing member 54 is pulled outward 25 against the resistance of the spring 57 until it clears the frame, it is then lowered with its rod or stud 58 down into the lower end of the slot 59, and is then turned at the stud to the position shown in dotted lines 30 in Fig. 3 which allows the upper member 52 to be unhooked from the shaft, whereupon the frame 37—38 and the pounders and their cylinders are all in one structure lifted out of the main cylinder 10 so that clothes 35 may be removed from and others placed into said cylinder.

The middle of the frame is offset downwardly and formed into an upper and a lower bar; the upper bar 63 (see Figs. 7, 9 10 and 10) bears up under the hub of the pinion 35 and has a rearward notch 64 fitting the front side of the shaft 12; the lower bar, 65, is formed with a notch or bearing 66 also fitting the front half of shaft 12, but 5 upon this bar is pivoted at 67 a member 68 having a notch 69 bearing against the rear side of shaft 12. The free end of this member or latch is provided with an embossment 70 within which is arranged a slidable locking pin 71, having a spring 72 tending to hold it engaged in a cavity 73 (see Figs. 7 and 9) in the rigid bar 65. When the frame is to be removed from the machine this pin 71 is grasped by its head and raised and 5 the bearing member 68 swings open for the vertical shaft to escape from the frame.

In the operation of the machine for dry-cleaning, the tub is filled about half full of gasolene, the clothes placed in the cylinder 0 10, the pounders are placed upon them, the gear 33 moved out of mesh with the pinion 35. The support 29 is thrown out of contact with the arm or lever 21. As the shaft 15 is then rotated the mutilated gears 36, 36^a 5 will engage the racks of the pounders and

push them in alternate order down into the clothes in the gasolene, and when each pounder cylinder 42 is sufficiently resisted by the clothes to compress the spring 47 the latter yields and lets the piston 41 descend 70 in the cylinder and expel air from it into the clothes until the gear has lost its engagement with the rack when the springs 50 will instantly raise the piston and pounder to normal position, where it remains until the 75 toothed part of the gear engages the rack again and repeats the stroke. As the pounder ascends and the piston is being drawn upward by the springs 50 an agitating and cleansing suction takes place in the clothes 80 until the pounder cylinder gets above the surface of the gasolene when it will instantly get filled with fresh air and thus ready for the next downward plunge. While this takes place the main cylinder 10 is slowly 85 rotated by the friction pulley 25.

When the clothes have thus been cleaned the cover 8 is removed, the box or bearing members 54 and 68 thrown open, the arm 21 raised upon the support 29, the frame 37 and 90 the pounders removed from the machine, the gear 33 put in mesh with the pinion 35, the cock 7 opened and the shaft 15 rotated, the faster the better, so as to cause the centrifugal force to extract the gasolene from the 95 clothes, whereupon the clothes are removed from the machine.

If the machine is to be used for common clothes washing the operation is the same as that already described for dry-cleaning, 100 with the exception that instead of gasolene water and soap, and if so desired some kerosene may be used.

What I claim is:

1. In a machine of the class described, a 105 stationary cylindrical tub, a skeleton tub rotatably mounted in the middle thereof and having a vertical shaft, a horizontal drive shaft journaled across the top of the stationary tub and having operative connection 110 with the shaft of the skeleton tub to rotate it, a frame detachably journaled on both of said shafts, two pounders arranged to work in the skeleton tub and having each a vertical rod slidable in the frame and at one 115 side provided with a rack, two reversely arranged mutilated gears fixed on the drive shaft and arranged to engage and push downwardly said racks in alternate order, and springs arranged to raise the pounders 120 whenever the toothed portions of the gears are turned away from the racks.

2. In a machine of the class described, a stationary tub, a suitable frame therein, a rotary tub mounted centrally within the stationary tub outside said frame, two pounders arranged to operate in the rotary tub, each of said pounders comprising a cylindrical hollow body with an apertured top, and a piston movable in the cylinder and 130

- having a pounder rod extending upwardly through the apertured top and into the frame, a drive shaft journaled across the stationary tub and in the frame and provided with means for driving the pounders alternately downward and there releasing them; two springs attached to each piston and to the frame and extending through the apertures in the head of the cylinder part of the pounder, to raise the piston and cylinder to the upper position of each stroke.
3. In a machine of the class described, a vertical shaft and a horizontal drive shaft geared thereto, a frame detachably journaled on the two shafts, two pounders having each a rack-shaped rod slidably guided in the frame and the lower end provided with a piston, two mutilated gears fixed on the drive shaft and arranged to push the racks downward in alternate order, a downwardly open cylindrical member fitted about each
- piston and having in its top two apertures, two pulling coil springs connected with the piston through said apertures and having their upper ends attached to the frame, a 25 collar on each piston rod or pounder rod, a compression coil spring encircling the piston rod between the collar and the top of the cylindrical member of the pounder, and a short cushion coil spring on the rod close 30 above the collar so as to contact with the frame, and stop the upward stroke of the entire pounder with the least possible noise.
4. The structure specified in claim 3, said cylindrical pounder members having each in 35 its open bottom end a spider, and a vertical central rod fixed in the spider and slidably inserted in the piston rod, the latter being for that purpose tubular at least as far as said spider rod enters into it.

In testimony whereof I affix my signature.
ANDREW B. MILLER.
